JAMES KEITH, OF LONDON, ENGLAND.

DESIGN FOR A CASING FOR AIR-CIRCULATORS.

41,269.

Specification for Design.

Patented Mar. 28, 1911.

Application filed January 11, 1911. Serial No. 602,111. Term of patent 14 years.

To all whom it may concern:

Be it known that I, JAMES KEITH, a subject of the King of Great Britain and Ireland, residing at the city of London, England, have invented a new, original, and ornamental Design for Casings for Air-Circulators, of which the following is a specification, reference being had to the accompanying drawing, forming part thereof.

The figure is a perspective view, illustrating my design.

I claim:

The ornamental design for a casing for an air circulator, as shown.

In testimony whereof, I have signed my name to this specification in the presence of two subscribing witnesses.

JAMES KEITH.

Witnesses:

JOHN WHITE HAMPSHEIR,
CHARLES JOHN SAMPSON.
